UNITED STATES PATENT OFFICE.

ISRAIL L. ROSENFELD, OF NEW YORK, N. Y., ASSIGNOR OF ONE-FOURTH OF HIS RIGHT TO MAKS J. LASAR AND ADOLF J. GRINBERG, OF SAME PLACE.

SNOW-PLOW.

SPECIFICATION forming part of Letters Patent No. 227,841, dated May 18, 1880.

Application filed February 24, 1880.

To all whom it may concern:

Be it known that I, ISRAIL L. ROSENFELD, of the city, county, and State of New York, have invented a new and useful Improvement 5 in Snow-Plows, which improvement is fully set forth in the following specification, reference being had to the accompanying drawings, in which—

Figure 1 represents a longitudinal vertical 10 section of my apparatus. Fig. 2 is a horizontal section thereof. Fig. 3 is an end view of the same. Fig. 4 is a detail view of parts.

Similar letters indicate corresponding parts.

My invention relates to plows for removing 15 snow from railroads, and has for its object the production of an apparatus adapted to the removal of snow from cuts or inclosed spaces, as well as other portions of a road.

It consists in certain novel combinations of 20 parts, hereinafter fully described, and pointed out in the claims, a preliminary description thereof being therefore deemed unnecessary.

In the drawings, the letter A designates a 25 platform, which is made of a convenient length and preferably wider than the gage of the road, while it is inclined in a longitudinal direction, the lower part or end thereof constituting the head or front of the plow and being close to the rails but running freely over them.

30 This inclined platform A is mounted on a truck, of which a are the wheels and b the axles, and above the platform are arranged two (more or less) clearers or sweepers, B B, which, in this example, consist, respectively, 35 of a shaft, c, and a series of blades, d, and both of which receive a revolving motion from the rear truck-axle, b, by gearing next described, so that they are adapted to throw from the platform the snow that is taken up thereon, 40 as hereinafter explained.

The motion of the rear truck-axle, b, is transmitted to the shafts of the clearers B B through the medium of vertical shafts or spindles C C, which are geared with the truck-axle by cog-wheels D, E, and F, and geared with the respective clearer-shafts by cog-wheels G or G' and H. The wheels E are transfer-wheels, and are arranged to be thrown out of gear by a

mechanism illustrated in Fig. 4, so that the clearers may be left stationary if desirable. 50

The shafts of the clearers B B have their bearings at the forward end in a cross-head, I, and at the rear end in independent blocks or boxes J J, both of which bearings I J J are adjustable in a vertical direction, so that the 55 clearers may be set or moved to different levels—namely, toward or away from the platform A—in order to adapt the same to the height of the snow on the platform.

In order that the clearer-shafts may remain 60 in gear with their driving-spindles C C when the clearers B B are set up or down by means of their adjustable bearings I J J, the wheels G G', either of which acts on the wheel H at the rear end of the clearer-shafts, are arranged 65 to move with the clearers in a vertical direction, this purpose being accomplished by arranging the wheels G G' on feather-keys e, so that they are adapted to slide on the spindles, and attaching to the block-bearings J J, respectively, an arm, f, for holding the wheels G G' in their positions on the spindles. 70

The cross-head I, forming the bearings for the forward ends of the clearer-shafts, is arranged to slide on a standard, K, rising from 75 the platform A, and to the same is connected one end of a chain or rope, g, which runs over pulleys h, and the other end of which is connected to a drum or windlass, L, so that by turning the latter in one or the other direction, 80 and thereby winding up or unwinding the chain, the cross-head I, together with the forward ends of the shafts carrying the clearers, can be raised or lowered.

The blocks or boxes J J, forming the bearings for the rear ends of the clearer-shafts, are arranged to slide in vertical guideways i i, and are each connected to an endless chain or rope, j, running over pulleys k k, so that by turning either of these pulleys in one or the other direction the block-bearings are raised or lowered by means of the endless chains, with a like adjustment of the rear ends of the clearers. 85

The lower pulleys to the endless chains j j are mounted on shafts O O, which respectively carry a cog-wheel, l, meshing with a pin- 95

ion, *m*, on whose shaft is mounted a crank, *n*, so that a revolving motion can be imparted to the pulley-shafts for the purpose of operating the adjusting-chains *jj* by means of the cranks.

5 The pulley-shafts *O O* are each geared with a shaft, *P*, carrying the drum *L*, by means of a chain or rope, *o*, running over pulleys *p p*, so that the drum-shaft *P* revolves with the pulley-shafts. An important result of this arrangement is that the bearings *I J J* at both ends of the clearers *B B* are set simultaneously, another result being that both of the pulley-shafts *O O* revolve whether the power is applied to one or the other of them, since the motion of one is transmitted to the other through the drum-shaft *P*. Provision is made, however, for setting the bearings *I J J* also independently of each other, as for regulating the angle of the clearers *B B*—namely, by mounting the drum-shaft *P* and the shafts of the upper pulleys to the endless chains *j j* in boxes *q q'*, which are held by set-screws *r r'*, and are thereby adapted to be set to slacken the chains *o o* or the chains *j j*.

25 In order to permit the setting of the clearers *B B* to various angles their shafts are swivelled at each end, as at *s s*.

The guideways *i i* for the block-bearings *J J* are formed in a wall, *Q*, which extends across the platform *A* at the upper or back part thereof, and serves to separate and protect the gearing and paraphernalia for driving and setting the clearers from the snow received on the platform.

35 With the guideways *i i* may be combined spring-slides for closing the space between them without interfering with the adjustment of the block-bearings.

It is desirable, under certain conditions, that 40 the clearers *B B* revolve in one and the same direction, whether the apparatus move forward or backward, and the object of the two wheels *G G'* on the driving-spindles *C C* is to render reversible the direction of rotation of 45 the clearers independently of the direction of movement of the apparatus. To accomplish this purpose the wheels *G G'* of each spindle are placed above and below the wheel *H*, in a position to gear therewith, but are held a sufficient distance apart from each other, as by a 50 collar, *t*, interposed between them, so that when one of such wheels is in gear with the wheel *H* the other remains out of gear therewith, as shown in Fig. 1, and the arm *f*, for 55 supporting the wheels on their spindle, is subjected to the action of a set-screw, *u*. This set-screw is a fixture of the respective blocks *J J*, and by its means the arm *f* may be elevated or lowered, whereby either of the wheels 60 *G G'* is thrown in gear with the wheel *H*, and the clearers *B B* are revolved in one or the other direction to any direction of movement of the apparatus.

At or near the forward end of the inclined 65 platform *A* is located a head-gate, *R*, whose function is to retain the snow on the platform

in the back movement of the apparatus. This head-gate is movable in a vertical direction, and is operated by means of a chain or rope, *v*, which runs over pulleys *w*, and is connected to a windlass, *S*, having combined therewith a ratchet-wheel, *x*, and stop-pawl *y*. For the purpose of supporting and guiding the head-gate *R* it is constructed with side arms, *T T*, which extend rearwardly from the upper 75 part thereof, and are pivoted to brackets *U* on the wall *Q*, so as to swing in a vertical plane.

On opposite sides, and on a rear portion of the apparatus, are vertical wings *V V*. The position of these wings is at the upper end of 80 the platform *A* and opposite to the back wall, *Q*, from the ends of which latter they extend rearwardly and outwardly, and to which they are attached by vertical hinge-joints *Z*, so that they are adapted to be swung to an outer or 85 normal position, or to be swung inward, as when they are not in use. For the purpose of sustaining the wings *V* in an outer position they have attached thereto braces *W*, while for locking the wings in an inner position they 90 have combined therewith catches *X*.

In their inner or closed positions the wings *V V* bear against posts *Y*, which are slotted for the passage of the braces *W* through them, and form the supports for the catches *X*. 95 These catches *X* consist of vertical slides, which are guided on the posts *Y*, and are subjected to the action of springs, having a tendency to force the same to a lower or locking position, while they are provided with slots *a a'*, 100 whereby they engage the braces *W* to hold shut the wings.

In applying my apparatus to the removal of snow from a railroad-cut the head-gate *R* is lifted, as indicated in dotted outline in Fig. 1, to free the forward end of the inclined platform *A*, and the apparatus is run into the snow, the clearers *B B* having previously been brought to an upper position and having been thrown out of gear. In this manner the snow 105 lying along the line of the road is taken up on the platform *A*, and when the latter is full the head-gate *R* is allowed to descend; whereby the snow resting on the platform is severed from the mass in advance of the plow. The 110 apparatus is then drawn backward, in which motion the snow is held on the platform by the head-gate *R*, and when the apparatus reaches a part of the road suitable for discharging the load of snow the head-gate is lifted and the 115 clearers *B B* are thrown in gear, while their bearings are gradually lowered, so that the clearers receive a compound revolving and downward motion, and free the platform of its load.

120 It is understood that prior to starting the clearers *B B* the reversing-gear is set to produce the proper revolution of the clearers—namely, to throw the snow off the platform—and when the apparatus is used on a road having a single track the clearers may be made to revolve in opposite directions for throwing the 125

snow to opposite sides of the road; but when it is used on a road having a double track the clearers are both made to revolve in one and the same direction for throwing the snow to one side of the road only, thereby avoiding its being thrown from one track to another. The foregoing operation is repeated until the cut has been entirely cleared of snow.

If it is desired to deposit the load of snow 10 at any one certain spot, provision is made for operating the clearers B B by other means than the truck-axle, as by hand.

When my apparatus is used on roads built on plains or highways the head-gate R is permanently elevated, or the same may be omitted, and the clearers B B are set to a short distance above the platform A, the operation 15 in that case being to take up the snow on the platform and throw the same to one or both 20 sides of the road as the apparatus advances.

In the forward motion of the plow the wings V V are set to an outer or normal position, and by their means the snow displaced by the action of the clearers B B is compacted, so 25 that it is not liable to fall back on the track; but when the whole is moved backward the wings are shut, so as to lie close up against the sides of the apparatus and run free of interruption from the snow.

30 What I claim as new, and desire to secure by Letters Patent, is—

1. In a snow-plow, the combination of a longitudinally - inclined platform mounted on a wheeled truck, longitudinal revolving clearers 35 arranged above the platform, vertically-adjustable bearings to the clearer-shafts, and adjusting mechanism acting simultaneously on the bearings at both ends of the clearer-shafts, the whole constructed and adapted to operate 40 substantially as described.

2. In a snow-plow, the combination of a longitudinally - inclined platform mounted on a wheeled truck, longitudinal revolving clearers arranged above the platform, vertically-adjustable bearings to the clearer - shafts, and gearing adapted to transmit motion from one 45 of the truck-axles to the clearer-shafts, so arranged that the latter may be moved to different levels by means of their bearings without being thrown out of gear, the whole constructed and adapted to operate substantially 50 as described.

3. In a snow-plow; the combination of a longitudinally - inclined platform mounted on a wheeled truck, longitudinal revolving clearers 55 above the platform, and gearing adapted to transmit motion from one of the truck-axles to the clearer-shafts, so constructed that the direction of rotation of the clearers is reversible independent of the direction of movement 60 of the apparatus, the whole constructed and adapted to operate substantially as described.

4. In a snow-plow, the combination of a longitudinally - inclined platform mounted on a wheeled truck, longitudinal revolving clearers 65 above the platform, a vertically-movable head-gate, arranged substantially as described, for the purpose of retaining the snow on the platform in the back movement of the apparatus, and means for elevating the head-gate. 70

5. In a snow-plow, the combination of a longitudinally - inclined platform mounted on a wheeled truck, longitudinal revolving clearers arranged above the platform, a head-gate constructed with side arms pivoted to swing in a 75 vertical plane for raising and lowering the head-gate, and means for elevating the head-gate, the whole constructed and adapted to operate substantially as described.

6. In a snow-plow, the combination of a longitudinally - inclined platform mounted on a wheeled truck, longitudinal revolving clearers above the platform, and vertical wings arranged on opposite sides and on a rear portion of the apparatus, substantially as described, for the purpose of compacting the 80 snow. 85

7. In a snow-plow, the combination of a longitudinally - inclined platform mounted on a wheeled truck, longitudinal revolving clearers 90 arranged above the platform, side wings mounted on vertical hinge-joints, braces attached to the side wings for sustaining the same in their outer or normal positions, and catches for locking the wings in an inner position, the whole constructed and adapted to 95 operate substantially as described.

In testimony that I claim the foregoing I have hereunto set my hand and seal this 31st day of January, 1879.

I. L. ROSENFELD. [L. S.]
